US0D1050961S

(12) **United States Design Patent** (10) **Patent No.:** **US D1,050,961 S**
(45) **Date of Patent:** **** Nov. 12, 2024**

(54) **PEDAL ASSEMBLY**

(71) Applicant: **AteamProducts LLC**, Pompton Lakes, NJ (US)

(72) Inventor: **Steven J Digerardo**, Pompton Lakes, NJ (US)

(**) Term: **15 Years**

(21) Appl. No.: **29/959,109**

(22) Filed: **Aug. 23, 2024**

(51) **LOC (14) Cl.** **12-11**

(52) **U.S. Cl.**

USPC **D12/125**

(58) **Field of Classification Search**

USPC D12/111, 125

CPC . B62M 3/00; B62M 3/08; B60N 3/063; B62J

25/00

(57) **CLAIM**

The ornamental design for a pedal assembly, as shown and described.

DESCRIPTION

FIG. 1 is a top-front-left perspective view of a pedal assembly, showing the new design;

FIG. 2 is a bottom-rear-right perspective view thereof;

FIG. 3 is a front elevation view thereof;

FIG. 4 is a rear elevation view thereof;

FIG. 5 is a left-side elevation view thereof;

FIG. 6 is a right-side elevation view thereof;

FIG. 7 is a top plan view thereof; and,

FIG. 8 is a bottom plan view thereof.

The broken lines depict portions of the pedal assembly that form no part of the claimed design.

1 Claim, 8 Drawing Sheets
